UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,201, dated March 29, 1881.

Application filed February 7, 1881. Term of patent 3½ years.

To all whom it may concern:

Be it known that I, HENRY HORAN, of East Orange, in the county of Essex and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of my new design.

A is a square figure, within which is a vine, 15 *s*, bearing leaves and flowers. The figure A is overlapped at one corner by the rectangular figure M, richly ornamented with branching leaves and foliage. This figure M also overlaps the figure L, which is inclosed by an irregular-patterned band, and has within it a rose-like flower surrounded by leaves and sprays. The figure M also overlaps the figure G, also inclosed within an irregular-patterned border, one portion of this border 20 being the figure *i* and another portion the figure *a*. Within this border is the vine *h*, bearing leaves and circular flowers.

The figure G borders on the circular figure B, which incloses a flowering bush, *o*, and is 30 identical with the figure B², overlapping the figure L.

The figure D borders on the figures G and B, and is very similar to the figure A, but cut off more at its lower front, where it is 35 overlapped by the rectangular figure E, richly ornamented with leaves and flowers, and with the spray *f*, composed of leaves and ferns, and which connects E with the figure H, of the form shown, and inclosed by a distinct 40 border.

The figure I has a background composed of small checkered squares, and a distinctly-marked border surrounding it, and contains a spray, *g*, of leaves and flowers, which is a part 45 of the vine *h*.

The figure C is separated from D by the patterned figure *d*, and from I by the patterned figure *b*, and contains a vine, *m*, with leaves and flowers thereon.

50 I claim—
